UNITED STATES PATENT OFFICE

ADOLF SCHMITT, OF GREVEN, GERMANY, ASSIGNOR TO MECHANISCHE SPINNEREI & WEBEREI GREVEN, HERMANN BIEDERLACK & CO., GREVEN, GERMANY, A CORPORATION OF GERMANY

DESIGN FOR A TEXTILE COVER OR SIMILAR ARTICLE OF MANUFACTURE

Application filed May 17, 1933. Serial No. 48,141. Term of patent 3½ years.

To all whom it may concern:

Be it known that I, ADOLF SCHMITT, a citizen of Germany, residing at Bahnhofstrasse 76, Greven, Germany, have invented a new, original, and ornamental Design for a Textile Cover or Similar Article of Manufacture, of which the following is a specification, reference being had to the accompanying drawing, forming a part thereof, and showing a face view of a textile cover embodying my design.

I claim:

The ornamental design for a textile cover or similar article of manufacture substantially as shown.

ADOLF SCHMITT.
